UNITED STATES PATENT OFFICE.

JOSEPH W. WERTZ, OF ANDERSON, INDIANA.

SELF-LIGHTING MATCH CASE.

1,274,967.

Specification of Letters Patent.

Patented Aug. 6, 1918.

Application filed October 11, 1917. Serial No. 195,991.

To all whom it may concern:

Be it known that I, JOSEPH W. WERTZ, a citizen of the United States of America, residing at Anderson, in the county of Madison and State of Indiana, have invented certain new and useful Improvements in Self-Lighting Match Cases, of which the following is a specification.

This invention relates to improvements in match strikers.

The prime object of the invention is to provide simple and inexpensive means for lighting a match, and elevating same in convenient position for use or removal from the casing.

A further object of the invention is to provide specific means for automatically lighting a match, and holding it in position while it is moved to cause the head to frictionally engage a friction surface.

The invention also comprehends specific improvements in the details of construction and arrangement of parts which will be hereinafter described, and particularly pointed out in the claims.

In the drawings:

Figure 1 is a perspective view of my improved match lighter,

Fig. 2 is a central vertical section, the parts being in position to ignite a match,

Fig. 3 is a transverse section on the line 3—3 of Fig. 2,

Fig. 4 is a plan view,

Fig. 5 is a front elevation with the upper portion in section, the parts being in position to hold a lighted match elevated,

Fig. 6 is an end view,

Fig. 7 is a detail perspective view of the match grip,

Fig. 8 is a detail perspective view of the match support.

1 indicates a casing, the main body portion of which is preferably formed from a single stamped sheet of metal, and comprises a front 1^a, back 2, and sides 3, suitably clenched at the adjacent ends of the blank, at 4. The front is formed with an opening 5, and the metal at the sides thereof is bent inwardly toward the back, as at 6 to form guides 7, which terminate some distance from the back, forming a space about the

width of a match. The tops of the sides are bent inwardly toward each other as at 8, to close the upper portion of the casing each side the opening 5. The back 2, terminates some distance from the top of the front 1, and is bent inwardly as shown at 9.

To the rear of the casing is fastened a flat resilient strip 10, which extends up to the level of the top of the sides 3, one end of the strip overlapping the rear edge of one side 3, while the opposite end is bent around the opposite side 3, and is formed with a notch 11. The bottom of the strip is bent inwardly at 12, and joins the top of the back to form the bottom of a match receiving pocket 13.

In the pocket 13, is a match support 14, pivoted at one end at 15. The match support is formed of resilient material, and in advance of the pivot 15, and when in set position rests on a pin 16. The free end of the support and to one side thereof is provided with a finger piece 17, and extending therefrom is a lug 18. The lug 18, is designed to engage in a notch 19, formed in the rear edge of one of the sides 3, adjacent the overlapping end of the resilient strip 10. This construction serves as a catch to hold the support in match lighting position, as will later appear.

In the pocket 13, is a match grip 20, pivoted at 21, under the finger piece 17, and its free end extending toward and beyond the pivot 15. The free end of the match holder is provided with an offset lug 22, on which the match rests when seated in the pocket, while about midway of the length of the match holder is a lateral lug 23, which lies in the path of the match support, and against which a match rests when seated in the pocket. The lower end of the lug 22, is slightly extended, and is sharpened as shown at 22^a.

Adjacent, and above the free end of the match grip, when the latter is in striking position, is a lug 24, which extends inwardly from the casing. The lower end of this lug is sharpened, and is above the plane of the top of the lug 22, as shown in Fig. 3.

Pivoted in a slot in one side of the casing, and in line with the pocket 13, is a small plunger 28, designed to engage one end of

a match to force the head against a friction surface 29, on the opposite side of the casing. Matches are inserted in the bottom of the casing, and a cover 30, is fitted thereover, 5 and a spring and plunger 31, serves to force the pile of matches to the top. In use the match support, and the match grip are depressed, and the lug 18, catches in the notch 19 which locks the parts in the position 10 shown in Fig. 3 preparatory to receiving a match. By inserting the thumb or finger in the opening 5, a match is drawn up against the wall 9, and behind the guide lips 7, and into the pocket 13.

15 After the match is positioned in the pocket, as shown in Fig. 3, the plunger 28 is forced inwardly to hold the head of the match in engagement with the friction surface 29, and continued pressure on the plunger will force the upper end of the box outwardly as shown in dotted lines in Fig. 5, and disengages lug 18 from its notch, the resilient match support, which is now under tension on the rod 16, quickly acts to throw 25 the headed end of the match upwardly, which rubs the head against the friction surface 29 and causes ignition. When the match support springs upwardly it engages the lug 23 and rocks the match grip upwardly, 30 and in this movement the end of the match is clamped between the lug 22 on the match grip, and the fixed lug 24 extending from the casing; as shown in Fig. 5.

The lug 24 is so disposed as to act as a fulcrum for the free end of the match when thrown upwardly by the lug 22 when the latter is thrown up by the resilient support. Then when the match contacts with the lug 24 and is tilted upwardly the lug 22 acts 40 as a wedge to grip the opposite side of the match, the sharpened end fitting into the wood and drives the sharpened edge of the lug 24 into the other side. By this means the lighted match is held in a substantially 45 vertical position, while the casing serves as a handle.

After the match is extinguished, slight pressure on the finger piece 17 of the match support will release the grip of the lugs, 50 and the stem may be removed.

From the foregoing description it will be seen that I have provided a simple and inexpensive device for effectually lighting matches, and automatically holding the lighted match in position to be used. The arrangement of the match support and the match grip is such that the elements act in conjunction to perform the desired function.

60 What I claim is:—

1. A match lighter comprising a casing having a friction surface, a resilient pivoted match support, means for holding the match support in set position, a pivoted match grip

operated by the match support, and a fixed 65 match grip positioned to coöperate with the pivoted match grip to hold a lighted match after the holding means is released.

2. A match lighter comprising a casing 70 having a friction surface on one wall thereof, a pivoted match support in the casing to support a match adjacent the friction surface, a catch to hold the match support in set position, a bar on which the match support rests to place it under tension when in latched position, and a device operated by the match support to hold the lighted match in elevated position after the match support is released.

3. A match lighter comprising a casing 80 having a friction surface on one wall thereof, a pivoted match support in the casing to support a match adjacent the friction surface, a catch to hold the match support in set position, a bar on which the match support rests to place it under tension when in latched position, a pivoted match grip operated by the match support, and a fixed 85 match grip which coöperates with the pivoted match grip to hold a match in elevated 90 position after the catch is released.

4. A match lighter comprising means for supporting a match, a plunger disposed above the plane of the match support to engage and move a match into striking position, a movable match grip having a lug to engage a match and operated by the match support when the latter is released by the action of the plunger, and a fixed match grip spaced from the lug and adapted to co- 100 operate with said lug to hold a lighted match in elevated position after the latch is released.

5. A match lighter comprising means for supporting and igniting a match, resilient 105 means for holding the match supporting means in set position, a movable match grip having a lug to engage a match and operated by the match support when the latter is resiliently operated, and a fixed match grip 110 in the casing which coöperates with the movable match grip to hold a match in elevated position after the resilient holding means is released, and a plunger located above the plane of the match supporting means to 115 force the match head into position to be ignited by friction and to actuate the resilient holding means to release the match supporting means.

6. A match lighter comprising a casing 120 formed with a transverse match pocket, and an inclined wall below same, the front of the casing having an opening, the edges of the side walls of the opening being inclined adjacent the pocket to form a passage for 125 a match to said pocket, a pivoted resilient match support in the pocket, means for placing the support under tension and means

for holding said support in set position, a fixed match grip in the casing, and a pivoted match grip operated by the support to position and hold a match elevated against the fixed match grip when the support is released.

In testimony whereof I affix my signature in the presence of two witnesses.
